UNITED STATES PATENT OFFICE.

HUGO HELLER, OF MILWAUKEE, WISCONSIN, ASSIGNOR TO ARTHUR C. KOOTZ, OF MILWAUKEE, WISCONSIN.

DESIGN FOR A LOUD SPEAKER.

Application filed October 28, 1926. Serial No. 19,511. Term of patent 3½ years.

To all whom it may concern:

Be it known that I, HUGO HELLER, a citizen of the United States, residing at Milwaukee, county of Milwaukee, and State of Wisconsin, have invented a new, original, and ornamental Design for Loud Speakers, of which the following is a specification, reference being had to the accompanying drawing, forming part thereof.

The drawing shows a front view of a loud speaker embodying this invention.

I claim:

The ornamental design for a loud speaker as shown.

HUGO HELLER.
